UNITED STATES PATENT OFFICE.

ALONZO GUSTAVIS REYNOLDS, OF OAKLAND, CALIFORNIA.

CONCRETE WALL.

Application filed January 20, 1920. Serial No. 352,707.

To all whom it may concern:

Be it known that I, ALONZO G. REYNOLDS, a citizen of the United States, residing at Oakland, in the county of Alameda, State 5 of California, have invented a new and useful Concrete Wall; and I do hereby declare the following to be a full, clear, and exact description of the invention, such as will enable others skilled in the art to which 10 it appertains to make and use the same.

The invention relates to concrete wall constructions and has for its object to provide a wall, wherein air pockets are provided. The wall being constructed from a series of 15 superimposed slabs forming outer and inner walls, said outer and inner walls are provided with means for holding them spaced so that a form may be placed between the same at or near the points where they join 20 or abut each other and columns may be poured between the walls, also to provide reinforcing rods or wire mesh in the slabs, said rods or mesh being bent and extending outwardly adjacent to their ends so that they 25 may be imbedded in the poured columns thereby forming a tying means for the slabs of each wall with the poured columns.

A further object is to provide a wall slab having its bottom and one of its vertical 30 ends provided with a curved notch or groove and the top and the other end with a correspondingly shaped rib so that when the slabs are superimposed and formed into courses, the ribs of one slab will engage 35 the grooves of the adjacent slabs thereby forming additional holding means when the slabs are formed into a wall.

With the above and other objects in view 40 the invention resides in the combination and arrangement of parts as hereinafter set forth, shown in the drawings, described and claimed, it being understood that changes in the precise embodiment of the invention may be made within the scope of what is claimed 45 without departing from the spirit of the invention.

In the drawings:—

Figure 1 is a view in elevation of a portion 50 of the wall constructed in accordance with the invention.

Figure 2 is a horizontal sectional view taken on line 2—2 of Figure 1.

Referring to the drawings, the numeral 1 designates a wall, which wall comprises outer and inner walls 2 and 3. The walls 55 2 and 3 are formed from a series of superimposed slabs 4. Slabs 4 being formed before being placed in the wall. Each slab 4 has two of its edges provided with a curved groove 5, which groove receives the curved 60 shaped rib 6 of the adjacent slab thereby forming means for preventing the displacement of the slabs in relation to each other. Each slab is provided with longitudinally 65 extending reinforcing 9, the ends of which project outwardly at substantially right angles to the slabs so that their portions 10 will be disposed between the spaced walls 3 and 4 adjacent the vertical joints. The portions 10 of the reinforcing being so disposed, it will be seen that when the columns 11 are formed said columns will be anchored 70 to the walls 2 and 3. To additionally brace the columns 11, vertically disposed reinforcing rods 12 are embedded therein. It 75 will be seen that a wall construction is provided wherein air pockets 13 are provided thereby reducing the amount of material required for building a wall and at the same time decreasing the cost of construction. 80 The air pockets also allow ventilation and prevent the collection of dampness within the body of the wall.

Rods 12 are held in relative position to each other during the pouring of the columns 11 by rods 14, which rods have their ends provided with hooks for engaging the rods 12. Rods 14 form additional reinforcing for the columns after they have been 85 formed.

The invention having been set forth what is claimed as new and useful is:—

A wall comprising spaced walls formed from plastic slabs, interlocking means between the vertical ends of said slabs and in vertical alignment, plastic columns disposed between spaced walls at the points of engagement of the slabs which slabs engage each other centrally of the column, horizontally disposed reinforcing rods extending through the slabs, the ends of said reinforcing rods extending inwardly at right angles from the slabs at points spaced from their ends, the inwardly extending portions 95 100

of the horizontally disposed reinforcing rods being bent to form outwardly extending hooks, said hooks being imbedded in the plastic columns, and vertically disposed reinforcing rods extending through said columns and through said hooks thereby tying the adjacent ends of the slabs to the columns.

In testimony whereof I have signed my name to this specification in the presence of two subscribing witnesses.

ALONZO GUSTAVIS REYNOLDS.
